Fig. 2.

Joseph. M. Downing of Bristol. Pa.
Letters Patent

Aug. 25, 1831

Dated August 25th 1831

The Schedule referred to in these Letters Patent, and making part of the same, containing a description in the words of the said Joseph M. Downing himself of his improvement in the Kiln for the burning of Lime with Anthracite Coal.

To all whom it may concern: Be it known, that I Joseph M. Downing, of Bristol, in the County of Bucks, and State of Pennsylvania, have made certain improvements in the construction of the Perpetual Kilns for the burning of Lime by means of Anthracite Coal, by which Quick Lime is obtained free from coke, and equal for all purposes to the best lime burnt with wood; and I do hereby declare that the following is a full and exact description of my mode of constructing and using the same. — Fig. 1, in the accompanying drawing, represents a front elevation of a double Kiln built on my principle, and is taken from one in actual use: the main body of this kiln is built of stone and is laid in strong sand and lime mortar; it is lined with brick, soap stone, or other material, which will stand fire; clay being used as a cement instead of mortar. A, is the aperture from which the lime is drawn; B, a regulating door or valve, for the draft of air; C, the arch, to support the breast of the kiln; and the dotted lines — d — show the general form of the interior, which is circular in its horizontal section, its vertical section being somewhat in the form of an egg truncated at each end and standing on the smaller one. Fig. 2, is the ground plan, the references to which, upon the drawing are sufficiently explanatory. The measurements are only relative, and are from their nature susceptible of considerable variation. When building this kiln I employ a gauge or pattern such as is represented at Fig. 3, the use of which is quite obvious, although great advantage is derived from its employment it may be dispensed with. In this Kiln, the arch bricks, or bars, in or across the bottom, or any other part, are dispensed with and the form given to the inside is such as allows the lime to settle down and be drawn from the aperture at the bottom without interrupting the progress of burning. In filling the kiln, in order to insure an equal and regular distribution of heat, the stones are broken so that the larger do not exceed six inches in diameter; the smaller ones are then placed round the outside, and the larger ones in the middle of the kiln, the interstices carefully filled with small ones, the whole intimately mixed with small coal in the proportion of about one part by measure of coal to four parts of broken stone, the exact proportion must however depend on the quantity

127X

of the straw and also of the coal.

What I claim as new is the described construction of the Kiln by which the coke, grates, &c. as usually employed to sustain the lime and fuel, are dispensed with, and the general form and construction as above described with the mode of filling them for the purpose of producing the beneficial results hereinbefore set forth.
